CLAIM

We claim the ornamental design for a media cartridge, as shown and described.

DESCRIPTION

FIG. 1 is a first perspective view of a media cartridge.

FIG. 2 is a second perspective view thereof.

FIG. 3 is a first side view thereof.

FIG. 4 is a second side view thereof.

FIG. 5 is a rear side view thereof.

FIG. 6 is a front side view thereof.

FIG. 7 is a bottom side view thereof; and,

FIG. 8 is a top side view thereof.

Broken lines showing portions of the article form no part of the claimed design.
